UNITED STATES PATENT OFFICE.

EDWIN JAMES STANTON, OF NEWBURYPORT, MASSACHUSETTS, ASSIGNOR
TO THE TOWLE MANUFACTURING COMPANY, OF SAME PLACE.

DESIGN FOR A HANDLE FOR SPOONS, FORKS, &c.

SPECIFICATION forming part of Design No. 17,637, dated August 16, 1887.

Application filed July 9, 1887. Serial No. 243,898. Term of patent 7 years.

To all whom it may concern:

Be it known that I, EDWIN JAMES STANTON, a citizen of the United States of America, residing at Newburyport, in the county of Essex, 5 of the State of Massachusetts, have invented and produced a new and original Design for the Ornamentation of Handles of Spoons or Forks, or various other articles; and I do hereby declare the same to be described in the following specification and represented in the accompanying drawing, which is a top view of a spoon having on its handle the design in question.

The design consists of the representation of 15 two four-leaved clovers, *a b*, arranged with a space, *c*, between them, each clover having radiating from it a series of stems, *d*, terminating in pointed leaves *e*. Connecting them at each edge of the handle is a corrugated border, 20 *f*, one of such borders being continued in oblique

directions across the handle, as shown at *f'* and *g'*. In the angular space between the two oblique portions *f'* and *g'* of the border is a series of rays, and in advance of the portion *g'* a series, *h*, of long curved leaves.

The leading features of the design are the two clovers with their stems and leaves and the borders extending between or arranged with them, as represented.

I claim—

The design for the ornamentation of a spoon or fork handle herein described and shown, the same consisting of the representation of the clovers, their stems and leaves, and the connecting corrugated borders, as set forth.

EDWIN JAMES STANTON.
